UNITED STATES PATENT OFFICE.

FREDERICK HACHMANN, OF ST. LOUIS, MISSOURI, ASSIGNOR TO WILLIAM H. GREGG,
OF ST. LOUIS, MISSOURI.

MANIFOLD-SALES-BOOK COVER AND TISSUE BOOK THEREFOR.

Application filed May 9, 1921. Serial No. 437,792.

To all whom it may concern:

Be it known that I, FREDERICK HACHMANN, a citizen of the United States, and resident of the city of St. Louis and State of Missouri, have invented certain new and useful Improvements in Manifold-Sales-Book Covers and Tissue Book Therefor, of which the following is a specification, containing a full, clear, and exact description, reference being had to the accompanying drawings, forming a part hereof.

My invention relates to improvements in manifold sales book covers and tissue books therefor, and the primary object is to construct a tissue book to be used in connection with manifold sales books, which tissue book has an enlargement along its binding.

A further object is to construct a cover for a manifold sales book which is provided with a socket so that a tissue book having an enlargement along its bound edge can be inserted and securely held therein.

In the drawings:

Fig. 1 is a side elevation of my device showing the tissue book in position in the sales book indicated by dotted lines;

Fig. 2 is a fragmental plan view of the tissue book showing the enlargement along its bound edge;

Fig. 3 is a fragmental plan view of the tissue book before being bound and showing the insert made use of to form the enlargement;

Fig. 4 is an enlarged vertical sectional view through a portion of the cover showing the socket and a portion of the tissue book secured therein;

Fig. 5 is a perspective view of the socket;

Fig. 6 is a perspective view of a modified form of socket; and

Fig. 7 is a vertical sectional view of the same.

In the construction of my device I employ a cover comprising a top 8 and a bottom 9. The bottom 9 has a vertical projection or back 10 formed integral therewith. The back 10, as well as the cover 8, is provided with a plurality of eyes through which a hinge wire 11 is inserted.

Hingedly connected to the bottom 9 is a leaf 12, which carries a clamp 13. This is for the purpose of securing the manifold sales book to the leaf 12. To the inside of the back 10 is secured a socket which consists of a base portion 14 and the socket

portion 15. This socket portion is approximately one-fourth of a cylinder or a quarter round in cross section.

The portion 14 is provided with openings 16, through which rivets 17 are passed for securing the socket to the back 10. Within this socket is inserted the tissue book 18 which consists of a plurality of tissue leaves 19 and the cover 20. The book is formed by folding the tissue leaves and cover upon themselves and then stitching the same near the folded portion.

Before the tissue leaves and cover are folded over, I make use of the insert 21, which may be either a cord, a wire, or similar material. This insert causes the enlargement 22 to be formed along the bound edge of the tissue book.

The tissue book is adapted to be inserted into the socket longitudinally, the eyes 75 formed on the back 10 extending close enough to the edge 23 of the socket to prevent the enlargement 22 from being pulled out.

In Figs. 6 and 7 I have shown a modified 80 form in which the socket consists of the right angular or L-shaped member 24. This L-shaped member is provided with a plurality of recesses or slits forming tongues 25 and 26. The tongues 25 are beaded along 85 their projecting edge, as at 27, while the tongues 26 are curved to form the socket which receives the edge 22 of the tissue book.

For stiffening purposes the portions 26 are provided with ribs 28 so that they will not 90 bend and release the tissue book. In this modified form the bead 27 and edge 29 of the portions 26 are close enough together to prevent the withdrawal of the edge 22.

While I have shown my modified form as 95 secured to a sales book which has a flexible back and in which the covers are made of other material than metal, it is obvious that this modification can also be attached to the cover shown in Fig. 1, without departing 100 from the spirit of my invention.

Having fully described my invention, what I claim is:

1. A cover for manifold sales books, comprising a top and a bottom cover having an 105 integrally formed back hingedly connected together, a socket having a base secured to said back adjacent its hinged connection, and a tissue book carried by said socket.

2. A manifold sales book cover and tissue 110

book therefor, comprising a top cover, a bottom cover having a back, a socket having a base secured to said back, and a tissue book having an enlargement along its bound edge, 5 said enlargement inserted longitudinally into said socket.

3. A manifold sales book cover and tissue book therefor, comprising a top cover having integrally formed eyes along one edge, a 10 bottom cover having a back formed integrally therewith, eyes formed on the upper

edge of said back, a hinge wire passing through the eyes for securing the top cover and back together, a socket having a base secured to said back, and a tissue book having 15 an enlargement along its bound edge inserted in said socket, said tissue book being held in place by said socket and the eyes formed on the back and the top cover.

In testimony whereof, I have signed my 20 name to this specification.

FREDERICK HACHMANN.
